UNITED STATES PATENT OFFICE

165,919

POWER TRIMMER

Stephen J. Hoff and Harry J. Hoff, Richmond,
Ind., assignors to Hoffco, Inc., Richmond, Ind.,
a corporation of Indiana

Application February 9, 1950, Serial No. 7,848

Term of patent 14 years

(Cl. D40—1)

To all whom it may concern:

Be it known that we, Stephen J. Hoff and Harry J. Hoff, both citizens of the United States, and both residing at Richmond, in the county of Wayne and State of Indiana, have invented a new, original, and ornamental Design for a Power Trimmer, of which the following is a specification, reference being had to the accompanying drawing, forming a part hereof.

We claim:

The ornamental design for a power trimmer, substantially as shown.

STEPHEN J. HOFF.
HARRY J. HOFF.
